UNITED STATES PATENT OFFICE.

GEORGE B. RITCHIE, OF TULSA, OKLAHOMA.

EXTENSION-STEP FOR RAILWAY-CARS.

1,250,659.

Specification of Letters Patent. Patented Dec. 18, 1917.

Application filed May 23, 1917. Serial No. 170,434.

To all whom it may concern:

Be it known that I, GEORGE B. RITCHIE, a citizen of the United States, residing at Tulsa, in the county of Tulsa, State of Oklahoma, have invented certain new and useful Improvements in Extension-Steps for Railway-Cars; and I do hereby declare the following to be a full, clear, and exact description of the invention, such as will enable others skilled in the art to which it appertains to make and use the same.

This invention is an improvement in vehicle steps and has particular reference to an extension-step for railway cars.

15 An object of the invention is to provide an improved support for the extension or foldable step, whereby the same may be readily extended to a position in close proximity to the ground and folded beneath the 20 lowermost relatively stationary step.

Another object is the provision of a step of this character which is simple in construction, easy to manufacture and effective in carrying out the purpose for which it is 25 designed.

The inventive idea involved is capable of receiving a variety of mechanical expressions, one of which, for the purpose of illustrating the invention, is shown in the accompanying drawing, wherein:—

Figure 1 is a side elevation of the extension step in folded position showing the same applied to the permanent steps of a railway car.

35 Fig. 2 is a similar view with the extension step in an extended or lowered position.

Fig. 3 is a vertical longitudinal section.

Fig. 4 is a rear elevation.

Referring more particularly to the accompanying drawing the numeral 5 indicates the vestibule platform of a railway car having the permanent steps 6 depending therefrom in the usual manner. The lower end of each of the sides of the steps 6 is preferably provided with a reinforcing plate 7 to which is pivotally connected at 8, a lateral extension 9 of a hanger 10 the body portion of which is secured longitudinally to the vertical edge of the riser section 11 of the foldable step by fasteners 13, the other end of the hanger 10 is also provided with a lateral extension 14 projecting in opposite direction to the extension 9 and pivotally connected, at 15, to a supporting arm

16 arranged in a horizontal position and 55 having its forward end engaged with and supporting the under side of the step 12, the forward ends of the arms 16 being connected by a brace rod 17. The rear ends of the supporting arms 16 are connected by a similar brace rod 18 so as to lend further rigidity to the arms 16 which are adjustable back and forth to raise and lower the step 12.

Means for adjusting the arm 16 preferably comprises the bars 19 secured to the under side of the platform 5, one of said bars having pivoted thereto, at 20 a vertically arranged operating lever 21 the upper end of which extends above the platform 5 70 within easy reach of the operator while the lower end is pivotally connected to the brace rod 18. The bar 19 opposite that to which the lever is secured also has pivoted thereto, at 22, the upper end of a supporting arm 75 23 also connected at its lower end to the rod 18. It will be apparent from this description that when the lever 21 is shifted to raise or lower the step 12, the arms 16 will be adjusted back and forth and rock the hangers 80 10 about their pivots thereby swinging the step to the desired position.

What is claimed is:—

The combination with a permanent step, of an extension step associated therewith 85 and including a riser section, a hanger for each end of the riser section having its intermediate portion secured longitudinally thereto and its ends provided with oppositely projecting extensions, one of which 90 is pivoted to the lowermost permanent step and the other pivoted to the bottom of the extension step, horizontal supporting arms engaging beneath said extension step, brace rods connecting the forward and rear ends 95 of said supporting arms, a pivoted operating lever connected to the rear brace rod for adjusting said arms to raise and lower said step, and a vertical supporting arm pivotally connected at one end to said permanent 100 step and at its other end to said rear brace rod.

In testimony whereof, I affix my signature in the presence of two witnesses.

GEORGE B. RITCHIE.

Witnesses:

H. T. LUTTS,
B. B. PYLE.
